[57] CLAIM

The ornamental design for a device for pressing cartridges, as shown.

DESCRIPTION

FIG. 1 is a front, top, right-side perspective view of a device for pressing cartridges showing my new design;

FIG. 2 is a bottom, rear, left-side perspective view thereof;

FIG. 3 is a left side elevational view thereof;

FIG. 4 is a right side elevational view thereof;

FIG. 5 is a top view thereof;

FIG. 6 is a bottom view thereof;

FIG. 7 is a front elevational view thereof; and,

FIG. 8 is a rear elevational view thereof.

The broken line showing is for illustrative purposes only and forms no part of the claimed design.
